UNITED STATES PATENT OFFICE.

ADAM R. BROWN AND WILLIAM H. BELL, OF SIMPSONVILLE, KENTUCKY.

PUMP.

SPECIFICATION forming part of Letters Patent No. 350,108, dated October 5, 1886.

Application filed February 5, 1886. Serial No. 190,941. (No model.)

To all whom it may concern:

Be it known that we, ADAM R. BROWN and WILLIAM H. BELL, of Simpsonville, in the county of Shelby and State of Kentucky, have 5 invented a new and useful Improvement in Pumps, of which the following is a specification, reference being had to the annexed drawing, which is a side sectional elevation of our improved pump.

10 The object of our invention is to provide a pump in which the valves will be submerged, while the piston and pump-cylinder will be located at the top of the well or cistern; also, to provide for the balancing of the column of 15 water in the discharge-pipe of the pump, so as to reduce the labor of pumping.

Our invention consists in the construction and combination of parts, as will be hereinafter fully described and claimed.

20 The water-box A, which is designed to be submerged in the water of the well or cistern, is divided into three compartments, *a b c*. The compartment *a* communicates with the water of the well through openings *d* in the bottom 25 of the water-box, and at the top of the compartment *a* is formed an apertured valve-seat, *e*, upon the top of which rests a valve, *f*, having a leather face and provided with a spindle, *g*, which extends through a central opening in the valve-seat and is provided with a stop, *h*. The apertured valve-seat *e'* at the bottom of the compartment *c* is covered by a leather-faced valve, *f'*, whose spindle *g'* extends through an aperture in the center of the 35 valve-seat into the compartment *b*, and is provided with a stop, *h'*. A discharge-pipe, *B*, communicates with the compartment *c* and extends up above the top of the well or cistern, and is provided with a curved discharge-nozzle, *C*. A pipe, *D*, communicating with the compartment *b* of the water-box A, is connected at its upper end with a pump-barrel, *E*, containing a piston, *i*, attached to a piston-rod, *j*, extending through the cap of the pump and 40 connected with the hand-lever *k*. The shorter arm of the hand-lever *k* is connected by a link, *l*, with a bracket, *m*, secured to the side of the pump.

45 The pump-barrel *E* is provided with a collar, *n*, which rests upon the platform of the well. In the side of the pump-barrel *E* is formed a small opening, *o*, which is closed by a valve,

p, carried by the angled lever *q*, which is pivoted in ears *r*, projecting from the side of the pump-barrel, and whose horizontal arm carries a weight, *s*, which tends to hold the valve *p* to its seat and thus close the hole *o*. A rod, *t*, extending upward from the weight *s* through the well-platform, is provided with a handle, *u*, above the well-platform.

50 The pump is operated by oscillating the handle *k*, moving the piston *i* up and down in the pump-barrel. When the piston *i* rises, the partial vacuum created in the compartment *b* of the water-box A causes the valve *f* to rise and permit water to enter into the compartment *b*. When the piston *i* descends, acting through the column of water or air contained by the pipe *D*, it exerts a pressure on the water contained in the compartment *b*, causing the valve *f* to close 65 and opening the valve *f'*, forcing water into the compartment *c* and through the discharge-pipe *B*. As the pipe *B* becomes filled with water, water rises also in the pipe *D*, the air contained by the pipe *D* being arranged to escape through the opening *o* or around the piston *i*, so that the column of water in the riser is counterbalanced by the column of water in the pipe *D*.

70 The pump-piston, when reciprocated, alternately draws water into the compartment *b* of the water-box A and discharges it through the valve *f'* into the riser. When it is desired to admit air into the pump-cylinder, to permit the water to run down in the pipe *D*, the longer 75 arm of the lever *q* is raised by means of the handle *u*, and air is allowed to enter the pump-barrel through the opening *o*.

75 By balancing the column of water in the riser as described the pump is made to operate with the application of little power, and it is rendered capable of working in a deep well.

Having thus described our invention, what we claim as new, and desire to secure by Letters Patent, is—

90 1. The combination, with the pump-barrel *E*, piston *i*, and an outwardly-opening valve in the pump-barrel below the point reached by the piston in its downstroke, of the water-box A, provided with compartments *a b c*, ap- 95 etered valve-seats *e e'*, and valves *f f'*, the riser *B*, and the pipe *D*, connecting the pump-barrel with the water-box, substantially as herein shown and described.

2. A pump formed of the water-box A, having compartments $a b c$, and provided with the apertured valve-seats $e e'$ and valves $f f'$, the riser B, discharge-nozzle C, the pipe D, pump-barrel E, provided with the opening o , the piston i , the lever k , and link l , the weighted lever q , carrying the valve p , and provided with

the handle u , all constructed and combined substantially as herein shown and described:
